UNITED STATES PATENT OFFICE.

BURTON CRAWFORD, OF CROSS ROADS, OHIO.

POST-HOLE-DIGGING MACHINE.

SPECIFICATION forming part of Letters Patent No. 280,585, dated July 3, 1883.

Application filed May 9, 1883. (No model.)

To all whom it may concern:

Be it known that I, BURTON CRAWFORD, of Cross Roads, in the county of Madison and State of Ohio, have invented certain new and 5 useful Improvements in Post-Hole-Digging Machines; and I do hereby declare that the following is a full, clear, and exact description of the invention, which will enable others skilled in the art to which it appertains to make and 10 use the same, reference being had to the accompanying drawings, which form a part of this specification, and in which—

Figure 1 is a perspective view of my improved machine for digging post-holes. Fig. 15 2 is a front elevation of the same. Fig. 3 is a sectional detail view through a part of the auger-shaft with its collar and collar-catch; and Figs. 4 and 5 are detail views, respectively, of the catch in the top part of the frame, and of 20 the lever and eccentric for operating the rack-bar.

Similar letters of reference indicate corresponding parts in all the figures.

My invention has relation to apparatus for 25 digging post-holes; and it consists in the detailed construction and combination of parts of a machine of that class, as hereinafter more fully set forth, having for its object to bore a hole of any desired depth by the exertion of a 30 minimum of power, and also to provide for the easy extraction of the auger from the hole.

In the accompanying two sheets of drawings, A indicates a vertical frame, which has ways *a*, and is fixed upon a truck, B, having 35 wheels C and tongue D. At the lower end of one of the side pieces of frame A is pivoted upon a bolt, e, the rack-bar E, which has an enlargement, F, through which is inserted the eccentric G, which is provided with a handle, 40 g, for turning it. The eccentric G and rack-bar E are so arranged relative to each other that by turning the handle *g* the rack-bar may be moved forward or back, so as to throw it into or out of gear with the gear-wheel H of 45 the sliding frame I. The latter is by preference of the shape shown in the drawings, bent at its upper end to form an arch, J, adapted to engage the spring-catch K, which is secured in the top cross-bar of the frame A and operated by a handle, k. By moving this handle 50 forward in the direction of the arrow, Fig. 4,

the catch or hook at its lower end is withdrawn from frame I J, so that this is allowed to drop in position for operating the machine. The sides I of the sliding frame I J is provided 55 with lugs or catches *i*, which fit into the grooved ways *a* in the sides of frame A.

L is a collar, which turns in bearings *l l* in the cross-bars of the sliding frame. This collar has a spring-catch, M, which is adapted to 60 engage holes *n* in the auger-shaft N, as shown more clearly in Fig. 3 of the drawings, so that by disengaging the catch from the auger-shaft frame I J, with its appurtenances, may be moved up or down upon shaft N.

The mechanism for rotating the auger-shaft consists of the drive-wheel H, which is operated by a crank, h, and meshes with the bevel-pinion O, fixed upon the top of collar L. To facilitate the operation of the machine I use a 70 fly-wheel, P, having a bevel-wheel, p, which also meshes with pinion O.

From the foregoing description, taken in connection with the drawings, the operation of my machine will readily be understood without requiring extended explanation.

In moving the machine from place to place, the sliding frame I J is suspended upon the spring-catch K at the upper end of the fixed frame A.

When it is desired to use the machine, the auger-shaft N (which may be provided with an auger of any approved construction) is inserted into collar L, and held in place therein by means of the spring-catch M. The frame is 85 then lowered by releasing it from the catch or hook K, when of its own weight it will fall down, so as to bring the auger in contact with the ground, when the hole is started by turning crank *h*. After a hole about one foot in 90 depth has been bored, collar L is released from the auger-shaft, and frame I J is raised a suitable distance so that the person operating the machine can turn the crank with ease, when it is again fastened by engaging catch M 95 with one of the apertures *n* in the auger-shaft. In this manner a hole of any suitable depth is bored, frame I J being gradually shifted upon the auger-shaft.

When it is desired to withdraw the auger 100 from the hole, the eccentric G is turned so as to throw the rack-bar E forward and cause it

to engage the teeth of the drive-wheel H, when, by turning crank h, the auger is lifted out of the hole.

Having thus described my invention, I claim 5 and desire to secure by Letters Patent of the United States—

The combination, in a machine for digging post-holes, of the fixed frame A, mounted up- 10 on the truck B, and having grooved ways a, rack-bar E, pivoted at the lower end of the frame, eccentric G, adapted to throw the rack- bar forward and back, spring-catch K, se- 15 cured in the upper part of the fixed frame, sliding frame I J, having guide-lugs i and bearings 77, collar L, having spring-catch M

and bevel-pinion O, drive-wheel H, having crank h, balance-wheel P, having bevel-pinion p, and auger-shaft N, provided with a series of apertures, n, the whole constructed and combined to operate substantially in the manner and for the purpose herein shown and set forth. 20

In testimony that I claim the foregoing as my own I have hereunto affixed my signature in presence of two witnesses.

BURTON CRAWFORD.
